Primary Examiner — Derrick Holland*Assistant Examiner* — Lauren Calve(74) *Attorney, Agent, or Firm* — Schultz & Associates, P.C.(57) **CLAIM**

The ornamental design for a tie rack, as shown and described.

DESCRIPTION

FIG. 1 is a perspective view of a tie rack showing my new design;

FIG. 2 is a side elevation view thereof;

FIG. 3 is a front elevation view thereof; and,

FIG. 4 is a top view thereof.

The broken lines shown represent unclaimed subject matter and form no part of the claimed design.

1 Claim, 3 Drawing Sheets(56)
